UNITED STATES PATENT OFFICE.

RAY E. DE CAMP, OF WILKINSBURG, PENNSYLVANIA, ASSIGNOR TO WESTINGHOUSE ELECTRIC & MANUFACTURING COMPANY, A CORPORATION OF PENNSYLVANIA.

RELAY.

1,392,251.

Specification of Letters Patent. Patented Sept. 27, 1921.

Application filed August 26, 1918. Serial No. 251,430.

To all whom it may concern:

Be it known that I, RAY E. DE CAMP, a citizen of the United States, and a resident of Wilkinsburg, in the county of Allegheny 5 and State of Pennsylvania, have invented a new and useful Improvement in Relays, of which the following is a specification.

My invention relates to electromagnets and electromagnetically actuated switches 10 for the control of electric circuits. In a more limited aspect, my invention relates to relays that are particularly adapted for unit-switch-control systems.

My invention is of the same general character as that forming the subject-matter of 15 my co-pending application for current-limit relay, Serial No. 241,259, filed June 21, 1918, in which the actuation of an armature by a magnetic field set up by current flowing 20 through a coil compresses a spring which thereupon permits another spring to actuate a second armature at the proper time in opposition to the force of the said field. The present invention relates to a relay 25 which differs in a number of particulars from that of my copending application. The relay is retained in its inoperative position by a compression spring which assists the electromagnet when the latter is energized. When the electromagnet is energized, a second and stronger spring, which 30 is placed under compression, tends to close the relay. The latter closes when the force exerted by the relatively strong spring exceeds 35 the combined forces of the magnet and the relatively weak spring.

The single figure of the drawing is a side elevation of my modified relay.

The insulating panel 1 carries brackets 40 2 and 3 supporting a coil 4 which, when energized by current flowing through it, creates a magnetic field for attracting two armatures 5 and 6. A compression spring 7 is mounted upon a non-magnetizable rod 8 45 and the force exerted by it may be adjusted by means of a nut 8^a. The rod 8 is slidably mounted in projections 9 and 10 which are rigidly connected to, or are integral parts of, the bracket 3. The projection 9 serves 50 also as a pole piece of the coil 4 for the armature 5, while the projection 10 is directly mounted upon the panel 1. One end of the rod 8 projects through an opening in the armature 6 and is provided with an abut-

ment or stop 11 for normally engaging this 55 armature. The spring 7 thus, in co-operation with the abutment 11, normally maintains the armature 6 and the rod 8 in the relative positions illustrated.

One end of the armature 5 is provided 60 with ears 13 which are pivotally mounted upon a shaft 14 secured to the bracket 2. A spring 14^a is connected, at one end, to a member 2^a secured to the bracket 2, and, at the other end, to a member 15 that is adjustably mounted upon the armature 5. 65 The spring 14^a thus tends to maintain the armature 5 in the position illustrated, out of contact with the rod 8.

The other end of the bracket 2 carries a 70 non-magnetizable U-shaped member 16 in the arms of which is mounted a shaft 17 to serve as a pivotal support for the armature 6. The armature 6 may normally be maintained in engagement with a member 12, secured to an interior portion of an opening in the bracket 3 by a weak spring 18, or, if the relay is so mounted that the panel 1 is above the other parts, the armature 6 will be maintained by gravity in the position illustrated, in which event, the spring 18 may be omitted. The member 12 is made of non-magnetizable material to prevent "freezing." 75

A magnetizable member 19 is supported 80 between the arms of the U-shaped member 16 and is longitudinally adjustable to vary the size of the gap 20 between its inner end and the adjacent end 21 of the armature 6. The free end of the armature 6 carries a contact member 24, which is adapted to co-operate with a stationary contact member 26 85 mounted upon the panel 1.

The operation is as follows: Upon current flowing through the coil 4, a magnetic 95 field is created which causes the armature 5 to be drawn toward the pole piece 9. The rod 8 is thereupon forced inwardly toward the panel 1 to move the abutment 11 out of engagement with the armature 6 and cause 100 the spring 7 to exert a force upon the armature 6 tending to move the contact member 24 into engagement with the contact member 26. If the current is above a previously selected safe value, the force of the magnetic field upon the armature 6, combined with that of the spring 18, predominates 105 over the force of the spring 7 and the arma-

ture will remain in engagement with the member 12. The ratio of the force exerted by the magnetic field to that exerted by the spring 7 may be varied by adjusting the nut 8^a or the member 19, or both. When the current falls to the selected safe value, the spring 7 will move the armature 6, in opposition to the diminished force of the magnetic field and that of the spring 18, to cause 10 the engagement of the contact members 24 and 26. In the event that the magnetic field becomes too weak to maintain the armature 5 in engagement with the pole piece 9, the spring 14^a will actuate the armature 5 into 15 the illustrated position. This movement is aided by the spring 18, which effects the disengagement of the contact members 24 and 26.

As in Fig. 4 of the above-mentioned application, the armature 5 may be provided with an extension 37, preferably of insulating material, which carries a switch member 38 for coöperating with one or more stationary switch members 39 and 54 for a purpose fully explained in my aforementioned application.

If desired, the armature 5 may be designed to control a plurality of armatures 6, as in my aforesaid application. Other changes will be apparent to those skilled in the art. I desire, therefore, that the appended claims be construed broadly.

I claim as my invention:

1. The combination with means for creating a magnetic field and a pair of armatures adapted to be actuated by the force of said field, of a relatively strong spring for actuating one of said armatures in opposition to said force, a relatively weak spring for assisting the force of said magnetic field to retain said one armature in its inoperative position and means for compressing the first-named spring to render it effective upon the actuation of said other armature.
- 45 2. The combination with a coil and an armature therefor, of a movable member, a stop member therefor, a relatively weak spring for biasing said movable member toward said stop member, and a relatively strong spring, said armature being adapted 50 to cause said second spring to actuate said

movable member against the force of the first-named spring.

3. In a switch mechanism, a bracket, a pair of members independently pivoted thereto, means for biasing said members to their inoperative positions, a third member slidably connected to one member of said pair, a spring for maintaining said slidably connected members in engagement, and means for attracting said pair of members, the other member of said pair being adapted to thereupon interrupt said engagement in opposition to the force of said spring.

4. The combination with a switch member 65 and a relatively weak spring tending to retain said member in its inoperative position, of a coil for retaining said member in its inoperative position so long as said coil is energized above a predetermined degree, an 70 armature member controlled by said coil, and a relatively strong spring controlled by said armature member to actuate said switch member.

5. The combination with a switch member 75 having a pivotal support at one end thereof, of a coil for retaining said switch member in its inoperative position so long as said coil is energized above a predetermined value, a spring for assisting the force of 80 said coil, a member yieldingly connected to said switch member, an armature member for actuating said yielding-connected member, and a second spring for biasing said armature member to its inoperative position. 85

6. The combination with an energizing coil and two armature members controlled in accordance with the degree of energization of said coil, of a spring for biasing each of said armature members to their respective inoperative positions, a member for engaging one of said armature members, and a spring tending to maintain the engagement of said members, one of said armature members operating to place said spring under 95 stress to effect the disengagement of said members and to effect the actuation of the other armature member.

In testimony whereof, I have hereunto subscribed my name this 22nd day of August, 1918.

RAY E. DE CAMP.
